UNITED STATES PATENT OFFICE.

MARTIN ALLEN BARBER, OF MONTREAL, QUEBEC, CANADA, ASSIGNOR OF TWO-FIFTHS
TO IRVIN GRIFFITH CLAYTON AND ONE-FIFTH TO ABRAHAM LINCOLN MOLER,
BOTH OF MONTREAL, QUEBEC, CANADA.

AUTOMATIC TRAIN-PIPE COUPLING.

1,161,373.

Specification of Letters Patent. Patented Nov. 23, 1915.

Application filed June 21, 1915. Serial No. 35,336.

To all whom it may concern:

Be it known that I, MARTIN ALLEN BARBER, a citizen of the United States of America, and resident of Montreal, Province of Quebec, Canada, have invented certain new and useful Improvements in Automatic Train-Pipe Couplings, and do hereby declare that the following is a full, clear, and exact description of the same.

10 This invention relates to devices for the automatic coupling of the signal, brake and steam pipes of railway cars and an object of the invention is to provide a strain equalizing connection between the coupler head and 15 its sustaining bracket.

The above with further objects and advantages will be hereinafter more fully described and particularly pointed out in the appended claims.

20 For full comprehension, however, of my invention reference should be had to the accompanying drawings forming a part of this specification in which similar reference characters indicate the same parts and 25 wherein:

Figure 1 is a side elevation of my improved coupler; Fig. 2 is a rear view thereof; Fig. 3 is a side elevation, partly broken away, of two engaging couplers; and Fig. 4 is a horizontal section on line 4—4 Fig. 1. Fig. 5 is a section on line 5—5 Fig. 1.

Referring now to these drawings, 2 indicates a portion of a car and 3 the draw-bar of the draft rigging mounted upon such car.

35 A coupler head sustaining bracket 4 is shown as suspended from the draw-bar although this bracket can be otherwise suitably supported from the car and consists of a downwardly extending member forked at 40 its lower end, that is having arms 5 at such end which are spaced transversely of the car to provide an opening extending longitudinally of the car for the accommodation of the means connecting the bracket to the coupler head as will be presently described.

The coupler head shown by way of example is of the type having a frame 6, a rearwardly extending shank 8 and train pipe apertures 9, 10 and 11, one being disposed centrally in line with the shank and the others respectively above and below the central aperture. The apertures have rearwardly extending nipples to which train pipes 12, 13 and 14 are respectively connected, the frame

being also formed with an opening 15 at one 55 side and an inclined projecting guide 16 at the other side adapted to enter an opening, in another coupler head, similar to opening 15 and guide the two coupler heads into engagement and bring their respective train 60 pipe apertures into register as shown in Fig. 3.

I have provided a novel connection between the bracket and coupler head and one which compensates for the movement of the 65 coupler head with respect to the bracket and equalizes the strain consequent upon such movement and a preferred construction of such connection will now be described.

The lower ends of arms 5 have round 70 openings 17 therein which loosely receive the ends of a transversely extending pin 18, the pin being rotatable and held against side-wise displacement by a head 18^a formed at one end and a cotter pin 19 passed through 75 the opposite end. The shank 8 passes rearwardly through an opening 20 formed transversely of the pin about midway between the bracket arms and a cotter 21 holds the shank from forward withdrawal, the ends of 80 the opening 20 being flared horizontally outwardly at 22 to permit of a lateral swinging of the coupler head, which latter also swings vertically with pin 18 as the pivot.

An equalizer member or bar 23 is located 85 between arms 5 and adapted to swing vertically and longitudinally of the car in unison with vertical swinging of the coupler head, such bar being carried by pin 18 preferably through the medium of forwardly extending 90 lugs 24 which are disposed about midway between the ends of the bar and are perforated and have the pin passed therethrough. The middle portion of bar 23 is apertured at 25 opposite the opening 20 to permit rearward. 95 movement of shank 8 and the ends of such bar have openings 26 therein to loosely receive the inner or rear ends of rods 27 which are pivoted at their outer or forward ends to the coupler head.

The rods 27 are respectively located preferably above and below the shank and inclined outwardly and rearwardly in opposite directions with respect to the latter, that is the upper one inclines upwardly and the lower one downwardly and the inner ends of such rods project rearwardly through the equalizer bar and have nuts 28 screwed

thereon to hold them in position. The projecting inner end of the upper rod also has an elongated button 29 screwed thereon, spanning the space between arms 5 and 5 adapted to bear against the rear edges of the latter, limit the forward swinging of the upper portion of the equalizer bar and uphold the coupler head when the latter is uncoupled and maintain such head in position 10 to engage with a mating coupler head. The nut 28 upon the upper rod is at the rear of button 29 and acts as a lock nut for the latter.

Each of the rods 27 has a coiled spring 31 15 encircling same and bearing between the outer side of the equalizer bar and a collar 32 formed upon the rod adjacent its forward end. The ends of the bar are forwardly offset at 32^a and rocking spring seats 32^b taking the form of washers are mounted upon 20 the rods between the offset ends of the bar and adjacent ends of the springs, the surfaces of these washers which bear against the bar being beveled inwardly from opposite sides to form a vertically disposed ridge 32^c to enable the spring seats to rock horizontally as the head swings laterally and thus avoid distortion of the springs during 25 such movement.

30 As illustrated in Fig. 3 a coupler constructed as above described is adapted to engage with a similar coupler upon another car to connect the train pipes, such engagement causing each coupler head with its 35 shank to move inwardly toward its respective equalizer bar and compress the springs 31, the resulting tension of which firmly holds the heads together and it will be apparent from this figure that should one car 40 be on a lower level than the other, this connection will not be impaired as the equalizer bar 23 will swing in unison with and maintain its angular position relatively to the coupler head and thus in avoiding excessive 45 strain on or distortion of any one spring, preserve the proper engagement of the coupler heads.

The pivotal connection between the forward end of rods 27 and the coupler head 50 accommodates the movement of the former as their inclination changes owing to the rearward movement of the coupler head and it is desired to pivot the rods to the latter through the medium of rearwardly extending 55 vertical lugs 33 formed respectively upon the top and bottom surfaces of the head, the collar 32 of each rod having a pair of spaced vertical lugs 34 extending forwardly therefrom on opposite sides of one 60 of the lugs 33 to which they are pivoted by a pin 35 passed through the overlapping lugs. The end of each of lugs 33 is rounded and in contact with the outer side of the collar between the lugs 34 which surface of 65 the collar is also rounded from top to bottom

to provide a convex bearing surface for the rounded lug.

The rounded lugs constantly bear against the convex surfaces and in this manner the end thrust of the rods whether the latter are 70 moving or still, is taken up directly therefrom by the rounded lugs and through them by the coupler head thus avoiding the exposure of the pivot pins to excessive strain and wear and also providing for an easy 75 movement of such rods.

What I claim is as follows:

1. In a train pipe connector, a bracket, a coupler head supported by the bracket and a connection between the bracket and head 80 permitting the latter to swing with respect to the former and including a plurality of springs and a device for equalizing the strain upon said springs resulting from the swinging of the coupler head. 85

2. In a train pipe connector, a bracket, a coupler head secured to the bracket, an equalizer bar and springs bearing between the head and equalizer bar.

3. In a train pipe connector, a bracket, a coupler head supported by the bracket, an equalizer bar and a pair of oppositely inclined springs bearing between the coupler head and equalizer bar. 90

4. In a train pipe connector, a bracket, a coupler head supported by the bracket and adapted to swing up and down, an equalizer bar carried by the bracket and adapted to swing in unison with the coupler head, a plurality of springs bearing between the 100 equalizer bar and coupling head and means for limiting the swinging movement of the bar and through it the downward movement of the coupler head. 95

5. In a train pipe coupler, a bracket having downwardly extending spaced arms, a pin supported at its ends by said arms and having a transverse opening therethrough, a bar located between the arms, and pivoted to the pin, a coupler head including a shank 110 which latter is located in the transverse opening of the pin and springs bearing between the coupler head and bar. 105

6. In a train pipe coupler, a bracket having downwardly extending spaced arms, a pin supported at its ends by said arms and having a transverse opening therethrough, the ends of which are flared in the longitudinal line of the pin, a bar located between the arms and pivoted to the pin, a coupler 115 head including a shank which latter is located in the transverse opening of the pin and springs bearing between the coupler head and bar. 120

7. In a train pipe coupler, a bracket having downwardly extending spaced arms, a pin supported at its ends by said arms and having a transverse opening therethrough, a bar located between the arms, pivoted to the pin and having openings at opposite 125 130

sides of the pin, a coupler head including a shank which latter is located in the transverse opening of the pin, rods pivoted to the coupler head respectively at opposite sides 5 and extending through the openings in said bar and springs encircling the rods and bearing between the coupler head and bar.

8. In a train pipe coupler, a bracket having downwardly extending spaced arms, a 10 pin supported at its ends by said arms and having a transverse opening therethrough, a bar located between the arms, pivoted to the pin and having top and bottom openings therein, a coupler head at the front of the bracket and including a shank which 15 latter extends rearwardly through the transverse opening of the pin, rods pivoted to the coupler head respectively at the top and bottom sides and extending rearwardly 20 through the top and bottom openings respectively of said bar, springs encircling the rods and bearing between the coupler head and bar, nuts upon the rear ends of the rods and a button upon the rear end 25 of the upper rod, such button spanning the space between the bracket arms and adapted to bear against the rear edges of the latter.

9. In a train pipe coupler, a bracket having downwardly extending spaced arms, a 30 pin supported at its ends by said arms and having a transverse opening therethrough, a bar located between the arms, pivoted to the pin and having top and bottom openings therein, a coupler head at the front of the bracket and including a shank which latter extends rearwardly through the transverse 35 opening of the pin, rods pivoted to the coupler head respectively at the top and bottom sides, and extending rearwardly 40 through the top and bottom openings respectively of said bar, springs encircling the rods and bearing between the coupler head and bar and a button upon the top rod, such button spanning the space between the 45 bracket arms and adapted to bear against the rear edges of the latter.

10. In a train pipe coupler, a bracket, a coupler head supported by the bracket, a member pivotally supported by the bracket, 50 rods, one of the ends of each of which is pivoted to the coupler head and has a shoulder formed thereon, the opposite ends of such rods extending loosely through the member, and springs encircling the rods and bearing between the shoulders and said member.

11. In a train pipe coupler, a bracket, a coupler head supported by the bracket,

rearwardly extending rounded lugs upon the coupler head, a member pivotally supported 60 by the bracket and having openings at opposite sides of the pivot point, rods, one end of each of which passes loosely through one of the openings in said pivoted member, the opposite ends of said rods having shoulders 65 thereon, a spring encircling each rod and bearing between the pivoted member and one face of said shoulder, spaced lugs extending from the opposite face of each of said shoulders and located upon opposite sides 70 of one of the rounded lugs and a pin pivoting the overlapping lugs together, those portions of the surfaces of the shoulders disposed between the spaced lugs being convex and having the rounded lugs respectively in 75 contact therewith.

12. In a train pipe coupler, a bracket, a coupler head supported by the bracket, a shank extending from the coupler head, a rod pivoted to the coupler head and carrying 80 a spring-seat, a spring bearing at one end against said spring-seat and a second spring-seat for the opposite end of the spring, whereby said spring resists movement of the coupler head. 85

13. In a train pipe coupler, a bracket, a coupler head supported by the bracket, a shank extending from the coupler head, a rod pivoted at one end to the coupler head, upheld at its opposite end by said bracket 90 and having a spring-seat thereon and a spring adapted to resist movement of the coupler head, one end of such spring bearing against the spring-seat.

14. In a train pipe connector, a bracket, 95 a coupler head supported by and adapted to swing with relation to the bracket, a member carried by the bracket and adapted to swing in unison with the coupler head, a rod attached at one end to the coupler head 100 and extending through said member, a spring encircling the rod and bearing between the head and member and a washer upon the rod and located between the member and adjacent end of the spring, the surface of said washer which bears against the member being beveled inwardly from opposite sides to form a vertically disposed ridge.

In testimony whereof, I have signed my name to this specification, in the presence of 110 two subscribing witnesses.

MARTIN ALI EN BARBER.
